UNITED STATES PATENT OFFICE

2,270,854

CYLINDER DRESSING TOOL

Herbert A. Berkman, Chicago, Ill., assignor to
 Zim Manufacturing Company, a corporation of
 Illinois

Application March 8, 1940, Serial No. 322,933

6 Claims. (CL. 51—184.2)

In my prior Patent No. 2,136,350, dated November 8, 1938, I have illustrated a tool for removing ridges which form in engine cylinders by reason of the fact that the pistons do not travel clear to the ends of the cylinders. Viewed in one of its aspects, the present invention may be said to have for its object to improve the construction of that tool while retaining the principle of operation thereof. In the patent the tool is shown as being of the reamer type. Instead of an edged cutter, an abrading element or hone may be employed. Viewed in another of its aspects, the present invention may be said to have for its object to modify the tool of the aforesaid patent to enable it successfully to grind or hone the interior of a cylinder.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a top plan view of one of my improved tools, equipped with an abrading element or hone; Fig. 2 is a section on line 2—2 of Fig. 1; Fig. 3 is a side view of a fragment of the tool, looking at the same from a point to the right of Fig. 2; Fig. 4 is a view, showing a still smaller fragment of the tool, and showing the side diametrically opposite that appearing in Fig. 3; and Fig. 5 is a section on line 5—5 of Fig. 2, with the swinging holder for the blade or hone and the adjustable plate on which the holder is mounted omitted.

Referring to the drawing, 1 represents a disk having a tubular stem 2 rising from the center thereof; there being a long bolt 3 extending through the stem and disk and into screw-threaded engagement with a spider 4 underlying the plate 1. As in my aforesaid patent, the spider cooperates with flat shoes 5 distributed around the same and adapted to be spread apart by the spider to clamp the plate 1 firmly within a cylinder, with the tubular post 2 coaxial with the cylinder and projecting from the latter. The only new thing in this part of the tool is that the post is shown as being quite long; the purpose being to permit the abrading tool or hone to be moved lengthwise of the same while being rotated, and thus prevent the cutting of grooves in the cylinder.

Overlying and resting upon the disk 1 is a plate 6 almost as large as the disk and having a sleeve-

like hub 7 of considerable length rising therefrom and surrounding the tubular post; the hub being considerably shorter than the post, so that the plate 6 and its hub may not only be rotated about the post but may also be moved up and down along the same, through a considerable distance.

The lower portion of the hub 7 has flat peripheral surfaces 8 while in the upper end are diametrically opposed bayonet slots 9 opening upwardly and adapted to receive pins or projections on the suitable sleeve wrench which may be lowered in a position surrounding the post and which serves to turn the plate 6 and also to raise and lower the same.

Overlying and resting upon the plate 6 is another plate 10 which is more nearly in the form of a complete disk than is the plate 6. The plate 6 is provided in the upper side with a radial groove 11 and the plate 10 has on the under side a tongue or rib 12 that fits slidably into this groove. There is also a large central window 14 in the plate 10 through which the hub 7 extends; the width of this window being equal to the distance between two opposed parallel flat faces on the hub 7. The long edges bounding the window are parallel to the tongue or rib 12, so that the tongue 12 cooperating with the groove 11 and the window 14 cooperating with the flat sided hub, both serve to prevent relative turning movements between the plates 6 and 10 while permitting the plate 10 to slide radially of the post upon the plate 6. The plates 6 and 10 may be fastened together by a screw 15 passing down through an elongated slot 16 in the plate 10 and into a screw-threaded hole 17 in the plate 6; the slot 16 being parallel with the groove 11 and the long sides of the window 14. Therefore, when the screw is loosened, the plate 10 may be slid back and forth and, in order to lock the plates together against relative sliding movements, it is only necessary to tighten the screw.

At one end of the plate 10 is a thick arm 18 connected thereto by a suitable hinge pin 19 that is parallel to the post 2. A long section at the free end of the arm is reduced in thickness, as indicated at 20, to finger-like proportions, and lies on top of the plate 10. Fixed on the plate 10 behind the part 20 is a socket 21 in which is seated a compression spring 22 that protrudes from the socket and bears against the rear face of the finger member 20. On the plate 10 in front of the finger 20 is an eccentric 24 or, rather, a cylindrical head or button having a stem 25 arranged eccentrically thereof so that

when the head or button is turned in one direction it pushes the finger inwardly or rearwardly against the resistance of the spring. The head or button 24 has in the top a saw cut or kerf 26 to receive a screw driver for turning the same.

The member for performing the work on the cylinder, whether it be a cutting blade or a hone, is mounted on the arm 18, about midway between the ends thereof. In the arrangement shown, this element comprises a long narrow hone 27 set in a metal shoe 28 having a rearwardly projecting ear 29. In the outer or front edge of the arm 18 is a wide notch 30 extending from top to bottom, and extending rearwardly from this notch into the body of the arm is a pocket 31. The shoe in its holder stands upright in the notch, while the ear extends into the pocket 31. A pin 32 extends through the ear and the solid portions of the arm on opposite sides of the ear to support the hone for swinging movements about an axis parallel with the top of the disk 1, namely at right angles to the axis of the post 2. The hone does not bottom in the notch when it stands parallel with the post, so that it is free to rock through a limited angle to adjust itself to the face of the cylinder wall.

It will be seen that by placing the spring 22 behind the free end of the arm 18, with the hone or cutter located at about the middle of the arm, the spring exerts a powerful leverage on the work-engaging element and may therefore be much weaker or softer than is a spring lying near the hinge. This is made possible by employing as a supporting member for the arm 18 a plate which is almost a complete disk. Not only does this construction provide a more satisfactory control of the yielding pressure on the work-engaging element than in my earlier device but, because of the broad bearing that the plate 10 has on the plate 6, the device as a whole is much sturdier and in less danger of chattering than is the case where the work-engaging element is carried from a series of arms, one supporting another, with the work-engaging element at one end of the series and the arm at the other end of the series being rotatably supported by the post. It will also be seen that by supporting the work-engaging element so that it may rock in a plane radial to the cylinder which is being treated, and moving the element lengthwise of the cylinder as it is being rotated, about the axis of the cylinder, the surface which is being treated will always be left smooth and free from grooves or scratches.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. A machine for dressing the interior of a cylinder comprising a member adapted to be secured in a cylinder, an element rotatable on said

member about the axis of the cylinder, a tool holder movably mounted on said member, and a long work-engaging tool mounted on said holder for rocking movements about an axis lying behind the same remote from both ends and at right angles to the axis of the cylinder.

5 2. A machine for dressing the interior of a cylinder comprising a member adapted to be secured in a cylinder, an element rotatable on said member about the axis of the cylinder, a tool holder hinged to said member for swinging movements about an axis parallel to the aforesaid axis, and a work-engaging tool mounted on said holder for rocking movements transverse to the said hinge axis.

10 3. In a machine for treating cylinders, a member having a flat bearing surface and a post projecting from such surface, means to secure said member in a cylinder with the post coaxial with the latter, a flat plate resting on said bearing surface and having a hub surrounding said post, a second plate overlying the first plate and interlocked therewith so as to be slidable thereon in a given direction, the second plate having therein 20 an elongated window through which said hub projects.

15 4. A machine for dressing the interior of a cylinder comprising a member adapted to be secured in a cylinder, an element rotatable on said member about the axis of the cylinder, a tool holder hinged at one end to said member for swinging movements about an axis parallel to the aforesaid axis, a work-engaging tool mounted on said holder for rocking movements transverse to the said hinge axis, and a compression spring positioned behind the free end of said holder and engaged at its ends with the holder and with a part fixed to said element.

25 5. A machine for dressing the interior of a cylinder comprising a member having a long post thereon, means to secure said member in a cylinder with said post arranged axially of the latter, and a support for a work-engaging element mounted on the post for movements lengthwise of and also around the latter, said support having a hub surrounding the post and provided at its free end with bayonet slots to receive pins on an instrument for turning the support and also moving it along the post.

30 6. In a machine for treating cylinders, a disk having a post projecting from the center thereof, means to secure said disk in a cylinder with the post coaxial with the latter, a flat plate resting on said bearing disk and having a hub surrounding said post, a second flat plate overlying the first plate and interlocked therewith so as to be slidable thereon in a given direction and to be held against rotation relatively thereto, the second plate having therein an elongated window through which said hub projects, a device for fastening said plates together against all relative movements, and a tool holder movably mounted on said second plate.
